(57) **CLAIM**

The ornamental design for a yoga roller, as shown and described.

DESCRIPTION

FIG. 1 is a side perspective view of a yoga roller showing our new design;

FIG. 2 is a front perspective view thereof;

FIG. 3 is a front view thereof, the rear view being a mirror image thereof;

FIG. 4 is a left-side view thereof, the right-side view being a mirror image thereof; and,

FIG. 5 is a top view thereof, the bottom view being a mirror image thereof.

1 Claim, 5 Drawing Sheets(56)
